UNITED STATES PATENT OFFICE.

LOUIS M. A. MUNTZ, OF WINONA, MINNESOTA.

RESPIRATOR.

SPECIFICATION forming part of Letters Patent No. 703,948, dated July 1, 1902.

Application filed February 4, 1902. Serial No. 92,539. (No model.)

To all whom it may concern:

Be it known that I, LOUIS M. A. MUNTZ, a citizen of the United States, residing at Winona, in the county of Winona and State of Minnesota, have invented new and useful Improvements in Respirators, of which the following is a specification.

This invention relates to apparatus which when properly fitted and secured upon the head of any person will permit the wearer to enter and remain with perfect safety in rooms or other places wherein the air is charged with noxious gases or vapors or smoke.

The invention is particularly adapted for use by firemen and miners, but of course could be used wherever a similar device might be desired.

The object of the invention is to improve upon and provide a more efficient construction of respirator or fire-mask than has heretofore been produced, and the novel construction thereof will be clearly described hereinafter, pointed out in the claims, and illustrated in the accompanying drawings.

The invention consists in the construction and arrangement of the several parts, which will be more fully hereinafter described and claimed.

Figure 1 is a perspective view of a mask or respirator constructed in accordance with my invention. Fig. 2 is a vertical longitudinal sectional view of the same; and Fig. 3 is a transverse sectional view on the line 3-3, Fig. 2.

Similar numerals of reference are employed to indicate corresponding parts in the several views.

The numeral 1 designates an inclosing hood or mask adapted to cover the head, face, and neck and having a contracting-string 2, of tape or elastic, whereby the lower portion of the hood may be tightly drawn around the neck of the wearer. The front portion of the hood is cut away and the opening made therefore is covered by a metallic plate 3, carrying windows 4 and 4^a, positioned adjacent to the eyes of the wearer and intermediate the windows just referred to. The plate 3 is enlarged at 5 to accommodate the nose of the person using the same. On the interior walls of said enlarged portion are two oppositely-disposed spring-fingers 6 to bear against and close the

nostrils when the mask is in place, so that the person to whom it is applied will be compelled to breathe through his mouth. Below 55 the nose-receiving portion on the outside of the plate 3, projecting therefrom and at a point opposite the mouth, is a filter-box 7, preferably rectangular in cross-section and which carries the filtering material, carrying-case, and valves, to be hereinafter referred to.

An interior sleeve 8 is held normally within the free end of the box 7 by spring retaining-arms 9. This sleeve is provided on one end 65 with a screen of suitable mesh (designated by the reference-numeral 10) and forms a cover for the filter-carrying casing 11, on which it is sleeved. The casing 11 is open at its outer end adjacent to the wire mesh 10, but is contracted at its rear end to form a hollow cylindrical tube 12, communicating with the inlet cylinder or passage 13, projecting from the plate 3 and leading into the interior of the hood 1 through the passage 14. A mouthpiece 75 15 of suitable material is connected to the interior of the plate 3 to be engaged by the lips of the wearer to assist in drawing the outside atmosphere into his lungs. The extreme end of the contracted portion of the 80 filter-material case is closed by a hinged valve, which will only be opened by inhalation and be held closed when the person exhales, as will be presently explained. In the filter is a perforated concavo-convex metal plate 16, 85 parallel to a disk 17, of wire-gauze or the like, said disk and plate being positioned in the rear portion of and against the rear wall 18 of the filter-material-carrying case to form a 90 backing, against which is positioned a sack 19, of filtering material, such as granulated carbon or charcoal, and between this sack and the open end of the case 11 is positioned a sponge of fine texture, which may be saturated with water or any other suitable liquid 95 to purge the inhaled air.

Projecting from one side of the tube 13 and communicating with the outside atmosphere at the side of the box 7 is a branch pipe 20, forming an outlet-duct, the free end of which 100 is normally closed by an outwardly-swinging hinged valve 21, which will remain closed when the wearer inhales, but will be opened by his exhalation.

22 designates a rectangular flange on the box 7 surrounding the valve 21 and engages a removable gauze cover 23, which protects said valve, but can be released in case it is 5 desirable to repair the same. A harness, comprising a head-strap 24 and the transverse strap 25, is connected to the plate 3 and is designed to more securely hold and retain the parts in proper position.

10 It will readily be seen that a very commendable feature of this invention is the adaptability of the several parts to be readily removed and easily assembled, making it possible to clean the same quickly and with practically no inconvenience, inasmuch as no extra tools are required.

To more securely protect the head of the wearer, a cap 26, of metal and of suitable construction, is employed, said cap being preferably cup-shaped to closely fit around the larger portion of the head, but leave a space between the crown of said cap and the top of the head, so that no inconvenience will result from the use.

25 Having thus fully described the invention, what is claimed as new is—

1. A device of the character described comprising a hood adapted to cover the head of the wearer, a metallic plate forming a portion 30 of said hood and provided with window-openings; a hollow projection adapted to fit the nose; springs secured to the opposite sides of the inner surface of said projection; a box projecting from said metallic plate; valves 35 within said box; a sleeve fitting within the outer end of said box and closed by a screen;

and oppositely-disposed springs secured to the box and engaging the outer end of the sleeve.

2. A device of the character described comprising a hood, a metallic plate forming a portion of the hood and having windows, a box projecting from said metallic plate, a filter-casing within said box, a valve controlling said filter-case, a laterally-extending exhalation-passage, a valve for said passage, a sleeve extending within the outer end of the box and fitting over the filter-casing, and means for detachably securing said sleeve in position. 45

3. A device of the character described comprising a hood, a metallic plate forming a portion of the hood and provided with window-openings, a hollow projection adapted to fit over the nose of the wearer, springs oppositely disposed within said hollow projection, a box 55 projecting from the metallic plate below the nose projection, a filter-case within said box formed with a contracted inner end, an inwardly-opening valve at the inner end of the filter-casing, a mouthpiece at the inner end of said box, a laterally-extending exhalation-pipe, an outwardly-opening valve at the end of said pipe, a sleeve fitting over the filter-casing and closed by a screen, and means for detachably securing said sleeve within the 60 outer end of the box.

In testimony whereof I affix my signature in presence of two witnesses.

LOUIS M. A. MUNTZ.
